UNITED STATES PATENT OFFICE

2,494,618

OPERATING MACHINERY FOR LOAD
HANDLING EQUIPMENT

William M. Huston, Lima, Ohio

Original application July 5, 1945, Serial No. 603,376. Divided and this application May 24, 1946, Serial No. 672,059

4 Claims. (Cl. 212—38)

1

This invention relates to load handling equipment and is concerned with a number of features of the arrangement of the operating machinery in load handling machines, of the type, for example, described and claimed in my copending application No. 603,376 entitled Load handling machines, filed July 5, 1945, of which this application is a division.

Although many features of the invention are of general applicability to load handling machines, certain of the features are of especial importance in machines of large size, adapted to handle heavy loads. Moreover, basically, the general arrangement of the operating machinery is adaptable to load handling machines of a variety of types including cranes, shovels, clam shells, draglines, and the like, although it is pointed out that certain features of the invention are of especial utility in large size cranes. Still further, the invention is especially useful in load handling machines of the type mounted on crawler trucks, adapted to be propelled by an engine or power plant carried by the rotating base. With the foregoing considerations in mind, the invention is hereinafter described and is illustrated in the accompanying drawings as applied to a crawler type crane of large size capable of handling heavy loads. In accordance with one important aspect of the invention, the arrangement of the machinery on the rotating base is such as to more effectively utilize the weight of the machinery than has been practicable heretofore in counterbalancing the load being handled by the boom. To this end, at least the primary, and preferably all, of the shafts utilized to perform the normal functions of the machine, such as swing, propel, hoisting, and boom hoisting, are located to the rear of the center of swing motion about which the rotating base is mounted on the crawler truck.

In the preferred embodiment, the machine of the invention is adapted to cooperate with the boom, the point of the boom being provided with sheaves adapted to cooperate with hoist cables which are respectively reeved on separately controllable hoist drums. The hoist drums, moreover, are separately mounted on hoist drum shafts, both of which are located to the rear of the center of swing motion. Thus, even with the employment of a plurality of hoist drum shafts, all of the primary operating shafts of the machinery are located to the rear of the center of swing motion, with the advantage above mentioned of contributing counterbalancing. It may be mentioned in this connection that in a ma-

2

chine of large size, as herein contemplated, weighing, for example, in the neighborhood of 300,000 pounds, as much as 30,000 to 40,000 pounds less counterweight is required than in an arrangement in which one or more of the primary shafts of the machinery are located ahead of the center of swing motion.

According to another feature of the invention two boom hoist drums are employed, these drums being arranged and mounted in a novel manner on the rotating base, as will further appear.

With reference to the machine as a whole, it may be said that the invention has, as an important general object, the provision of a load handling machine of large size capable of handling heavy loads, the operation and structure of the machine being simplified as much as is practicable, consistent with safety and ruggedness.

20 How the foregoing objects and advantages are obtained, together with others, will appear more fully from the following description referring to the accompany drawings which illustrate a crawler type crane constructed according to the present invention and in which—

Figure 1 is a somewhat diagrammatic side outline view of a crane embodying machinery arranged in accordance with the invention;

Figure 2 is a right-hand view on a scale enlarged as compared with Figure 1 showing the general arrangement of the machinery and its mounting on the rotating base, certain portions of this view being broken out and shown in section, as is mentioned in detail hereafter; and

35 Figure 3 is a top plan view of the mechanism shown in Figure 2.

Although the drawings illustrate the invention as applied to a crane, in which association various features of the invention are of special advantage, 40 it should be kept in mind that many aspects of the invention are equally applicable to other types of load handling machines. In fact, the basic or essential arrangements and structures of the rotating base, the machinery supports, and 45 the machinery itself may be used with little if any substitution of parts in machines such as shovels, draglines, clam shells, and the like. It is contemplated that when employing various features of the invention for machines other than cranes, different types of lagging may be associated with one or both of the hoist drums; and other clutch and drive mechanisms may be supported by the machinery frames and power shafts, in order to adapt the basic mechanism to perform the normal function of load handling ma-

3

chines of other types. To illustrate, in the case of a power shovel, a hoist drum may be employed to perform the function of dipper hoisting, and appropriate mechanisms will be added or substituted in order to take care of the functions of crowd-out and crowd-in.

Various features of general arrangement will now be described with reference to the accompanying drawings.

The rotating base of the machine generally indicated at 13 is mounted on the crawler truck 14 having a pair of crawler treads 15 on which the machine is adapted to be propelled on the ground. The rotating base is mounted for swing motion with respect to the truck about a vertical axis defined by a central bearing 16.

The rotating base serves to carry the engine 20 and machinery frames 21 (see Figures 2 and 3) and at its forward end, the base also provides a pin 22 for pivotal support of the foot end of the boom 23. The engine and the machinery on the rotating base are enclosed by a cab structure 24, and rising from the forward left hand corner of the rotating base is an operator's control tower 25.

The boom is adapted to be supported by a gantry structure including a pair of front compression legs 39 which are pinned at 40 to the rotating base adjacent to the pivot pin 22 for the boom. The gantry further includes pairs of rear tension legs 41 which at their outer ends are interconnected with the upper ends of the compression legs 39 by means of the gantry head shaft 42. Additional rear tension legs 43 are connected with the lower ends of legs 41, the legs 43 being extended downwardly to be pinned to the rotating base as at 45. The rear tension legs 41-43 are braced by diagonal braces 46 which are extended between the foot ends of the tension legs 41 and the upper edges of the machinery frames 21. The details of this gantry structure need not be considered herein since they form no part of the present invention per se, the same being described and claimed in my copending application Serial No. 603,380, filed July 5, 1945, issued April 20, 1948, as Patent No. 2,440,199, entitled Gantry structure.

The two ends of the boom hoist cable 48 are adapted to be reeved respectively on two boom hoist drums 52 and 53 (see Figure 3). Beginning at one drum 52 the boom hoist cable extends therefrom over sheaves at the gantry head shaft and from there to sling sheaves 49 and back again to the sheaves on the gantry head shaft, there being several runs of cable arranged in this manner. The cable is then associated with cross-over sheaves which are slung from the gantry head shaft and from there the cable passes in several runs between the head shaft and the sling sheaves 49, and the opposite end of the cable is ultimately reeved on the other boom hoist drum 53, as more fully described in my copending application No. 603,376, referred to above.

The gantry head shaft also serves as a reaction point for telescopic boom stop devices, one of these devices being shown in Figure 1 at 55. It will be seen that the outer ends of the stop devices 55 are connected with the boom 23 at a point in the central region of the boom. The specific structure of the stops 55 need not be considered herein since they form no part of the present invention per se, the same being described and claimed in my copending application Serial No. 603,378, filed July 5, 1945, and entitled Boom stops for load handling machines.

In considering the mounting of the machinery

on the rotating base 13 and the machinery frames 21, attention is directed to Figures 2 and 3, and it is noted that certain features of the rotating base itself constitute subject matter disclosed and claimed in my copending application Serial No. 603,382, filed July 5, 1945, issued January 4, 1949, as Patent No. 2,458,271, entitled Rotating base for load handling machines. From Figure 3 it will be seen that the rotating base comprises a

10 central base structure constituting the "back bone" of the machine which may be either a built-up construction, or, as shown in the drawings, may comprise a casting 13-a. All the major operating units of the machine are connected to 15 or anchored on this base casting. The central casting also serves to carry the lateral extension 13-b and 13-c providing a platform extending around the machinery. One or more counter-weights 70 are fastened to the central casting 13-a toward its rear end and the engine 20 is also mounted at the rear end. The engine shaft 71 which is supported in a bearing standard 14-a carries a sprocket cooperating with chain 12 which chain serves to drive the jack shaft 13 through the sprocket 14 (see Figures 2 and 3). The jack shaft is journaled in the right-hand machinery frame 21 and, also, in a support 75 which rises from an intermediate portion 13-c of the base casting 13-a. Another jack shaft 20 support 76 is provided just inside the plane of the sprocket 14. As clearly appears in Figure 3 the jack shaft 13 carries a pinion 77 which is keyed to the shaft, this pinion meshing with the gear 78, fixed on the rear hoist drum shaft 79 which 25 is journaled at the upper edges of the machinery frames 21-24 and extends across the machine to carry another gear 80 which is keyed to its opposite end. The front hoist drum shaft 81 is mounted at the upper edges of the machinery 30 frames ahead of the shaft 79, the shaft 81 having keyed thereon a gear 82 which meshes with gear 78 to receive power therefrom.

The horizontal reverse clutch shaft 83 is located intermediate the rear and front hoist shafts 45 79 and 81, shaft 83 being journaled in the machinery frames 21 in the lower region thereof and having associated therewith certain gears and 50 clutches described below for effecting the functions of swing and propel. At this point, it is noted that with the arrangement of shafts just described particularly the two drum shafts 79 and 81 adjacent the top of the machinery frames, and with shaft 83 mounted intermediate the drum shafts in the lower region of the machinery frames, the invention further contemplates a machinery frame interbrace 84 interconnecting the upper edges of the machinery frames in the region above the transverse shaft 83 and intermediate the two drum shafts 79 and 81.

The various functions of the machine are performed by the clutching of various operating units to the primary machine shafts already mentioned above; for example, shaft 79 carries a cable drum 85 which drum is adapted to cooperate with the hoist cable 36 shown in Figure 1 as extended upwardly to pass over the sheaves 35. Drum 85 is rotatively mounted on the shaft 79 and has a clutch housing 86 connected for rotation therewith (i. e., with the drum). It will be seen that upon engagement of the clutch associated therewith the clutch housing 86 is caused to rotate with the shaft 79, thereby rotating drum 85 to wind in the hoist cable 36 and thus 70 raise a load being handled by hook 37. When it

75

is desired to lower hook 37 the clutch is, of course, disengaged.

Referring now to the front drum shaft 81, this shaft carries a cable drum 106 adapted to cooperate with the main hoist cable 33 (see Figure 1) the drum 106 being rotatively mounted on shaft 81. Rotative with the drum 106 is a cylindrical braking surface 107 (see Figure 2) located at one side of the drum, and also a clutch housing 108 located at the other side of the drum. A friction brake band 107-a (see Figure 2) is adapted to cooperate with the brake surface 107. An internal expanding clutch is positioned within the clutch housing 108. Thus, the front hoist drum 106 is adapted to be connected with the shaft 81 by means of a clutch lying within the housing 108 in order to raise the main hook 34; and a brake 107-a associated with brake surface 107 is employed to control the rate and extent of lowering the hook 34.

Turning now to the boom hoist function, particular attention is directed to Figures 2 and 3. As there shown, the boom hoist drums 52 and 53 are mounted to rotate on boom hoist shaft 109, which is secured in the rotative base casting 13-a. One of the drums 52 lies in a recess or pocket 110 provided toward the left-hand side of the machine, and the other 53 in a larger pocket 111 provided toward the other side of the machine but extended centrally of the base sufficiently to accommodate the transmission or gear casing 112. Within this casing 112 shaft 109 carries a worm wheel 113 meshing with worm 114, constituting an irreversible worm drive. The worm is mounted on shaft 115 which is journaled in the casing 112. At its upper end, exteriorly of casing 112, shaft 115 carries a bevel pinion 116 meshing with a pair of bevel gears 117-118 which are respectively fastened to clutch housings 119 and 120. Each of the gear and clutch housing assemblies 117-119 and 118-120, is rotatively mounted on the jack shaft 13, and an internally expanding clutch is arranged within each one of the housings 119 and 120, these clutches being adapted to alternatively clutch one or the other of the housings to the jack shaft, so as to rotate bevel pinion 116 in one direction or the other and thereby provide for lowering or raising of the boom at will, it being understood that the ends of the boom hoist cable 48 are reeved respectively on the two boom hoist drums 52 and 53.

Turning now to the functions of swing and propel, it is first noted that provision is made for driving the horizontal reverse clutch shaft in either direction, the mechanism employed for this purpose being shown in Figures 2 and 3. At opposite ends of shaft 83, outside of the planes of the driving gearing 82 and 80, clutch housings 123 and 124 are mounted. A gear 125, meshing with gear 82, is fixed to rotate with clutch 123, this assembly (123-125) being rotatively mounted on shaft 83. Similarly, a gear 126, meshing with gear 80, is fixed to rotate with clutch housing 124, the two being rotative on the shaft 83. As seen in Figure 2, an internal expanding friction clutch 127 is arranged within the housing 123, being supported by a spider 128 which is keyed to shaft 83. Upon engagement of clutch band 127, the shaft 83 is caused to rotate with gear 125 which meshes with gear 82 on the front drum shaft 81. A similar clutch arrangement is associated with the clutch housing 124. Because of the fact that gears 80 and 82 rotate in opposite directions shaft 83 may be driven in opposite

directions by engagement of one or the other of the clutches at its outer ends.

Power is delivered from shaft 83 through bevel pinion 130 to a bevel gear 131, the latter being fixed at the upper end of the vertical reversing shaft 132, which shaft further carries a pinion 133 meshing with gear 134. Gear 134 is rotative with respect to the vertical swing shaft 135. Similarly, a gear 136 is rotative with respect to the vertical propel shaft 137, the two gears 134 and 136 intermeshing and therefore being rotated with the vertical reversing shaft 132 and with the gears 133 and 131 carried thereby.

The swing motion is effected by virtue of a pinion 138 fixed to the lower end of the vertical swing shaft and meshing with the internal ring gear 139 formed just inside of a circular track 18 on the truck structure 14. The vertical propel shaft 137 carries the bevel pinion 140 at its lower end which is adapted to cooperate with truck drive mechanism (not shown), for example, of the general type shown in the patent to this applicant and Cecil E. Jones, No. 2,387,268, issued October 23, 1945. Since the truck drive forms no part of the present invention per se, it need not be considered herein. Gear 134 is adapted to be clutched to the vertical swing shaft 135, and similarly, gear 136 is adapted to be clutched to the vertical propel shaft 137. For this purpose swing and propel dog clutches 141 and 142 are keyed to shafts 135 and 137 respectively, these clutches being arranged above the gears 134 and 136 and being adapted to be engaged alternatively.

By virtue of the arrangement described just above, the vertical swing shaft 135 and the vertical propel shaft 137 may alternatively be driven in either direction, the two directions of rotation being secured by virtue of engagement of one or the other of the clutches associated with the ends of the horizontal reverse clutch shaft 83.

The vertical swing shaft 135 also has a brake associated with its upper end, a braking surface 146 keyed to the outer end of the shaft 135 and surrounded by an external contracting brake band 147 (see Figures 2 and 3).

It is here noted that certain structural features of the machinery for performing the functions of swing and propel, as above described, are shown and claimed in my Patent No. 2,354-863, issued August 1, 1944, so that detailed description of these parts need not be given herein. But it is to be understood that certain of these parts shown in my prior patent are herein disclosed in a novel association with certain other parts of the machine of the present invention.

According to the foregoing, a load handling machine capable of handling large and heavy loads is provided, and notwithstanding the size and weight of the machine and its various parts and machinery the several working functions can be performed with ease and reliability.

I claim:

1. In a crawler type load handling machine having a rotating base mounted for swing motion and a boom carried by the base in front of the axis of swing motion, operating machinery carried by the base and comprising, in combination with an engine mounted at the rear of the rotating base, a jack shaft ahead of the engine and driven therefrom, a rear drum shaft ahead of the jack shaft and driven therefrom, a front drum shaft ahead of the rear drum shaft and driven therefrom, and a reverse shaft between the front and rear drum shafts and adapted to

be driven alternatively from one or the other of the drum shafts, said four shafts all being mounted to the rear of the axis of swing motion.

2. In a crawler type load handling machine having a rotating base mounted for swing motion and a boom carried by the base in front of the axis of swing motion, machinery frames extended fore-and-aft of the base, a power shaft toward the rear of the frames supported in part by at least one of the frames, a rear drum shaft ahead of the power shaft and driven therefrom, a front drum shaft ahead of the rear drum shaft and driven therefrom; and a transverse brace interconnecting the upper portions of the machinery frames in the region between said two drum shafts.

3. In a crawler type load handling machine having a rotating base mounted for swing motion and a boom carried by the base in front of the axis of swing motion, machinery frames extended fore-and-aft of the base, a power shaft toward the rear of the frames supported in part by at least one of the frames, a rear drum shaft ahead of the power shaft and driven therefrom, a front drum shaft ahead of the rear drum shaft and driven therefrom, a reverse shaft for swing and propel mounted in lower portions of the machinery frames intermediate the two drum shafts, and a transverse brace interconnecting the upper portions of the machinery frames in the region above said reverse shaft and intermediate said two drum shafts.

4. In a crawler type load handling machine having a rotating base mounted for swing motion on a crawler truck and a boom carried by the base in front of the axis of swing motion, 5 a pair of generally upright machinery frames extending fore-and-aft of the base in spaced parallel relation, a pair of drum shafts mounted one in front of the other adjacent the upper edges of the machinery frames, said drum shafts being adapted to perform working functions in association with the boom, a transversely extending shaft mounted in the machinery frames in lower portions thereof intermediate the drum shafts and being adapted to perform a working function in association with the crawler truck, and a transverse brace interconnecting the upper portions of the machinery frames in the region above said transversely extending shaft intermediate the drum shafts of said pair.

WILLIAM M. HUSTON.
